UNITED STATES PATENT OFFICE.

EARL A. WHEELER, OF LOS ANGELES, CALIFORNIA, ASSIGNOR TO STANDARD ROAD MAINTENANCE COMPANY, OF LOS ANGELES, CALIFORNIA, A CORPORATION OF NEVADA.

ROAD-WORKING MACHINE.

Application filed December 10, 1925. Serial No. 74,450.

This invention relates to road working machines and more particularly to a machine for removing surface irregularities from the surface of paved roads or highways or for 5 removing the surface covering of asphalt or the like from the concrete base preparatory to the laying of a new surface covering of asphalt or like material.

The machine disclosed in this application 10 is an improvement over that road working machine shown and described in Letters Patent issued to myself on July 28, 1925, for road grader and planer, No. 1,547,853.

In the leveling or grading or repairing of 15 surfaces of roads or highways which have an asphalt or asphalt-like covering, it is essential that a machine be provided that is adapted to operate with precision and must be adapted for a very close control of the cutting, grading or surfacing operation of the 20 tools employed. This is particularly necessary as it often occurs that the bond between the asphalt covering and the base of the highway or road is not perfect at all points and in 25 many cases is loose so that it is necessary to surface the same with extreme care so as to prevent the breaking of the loose bond which holds the surface covering to the base. As this machine is constructed for the eliminating 30 of ruts and bumps on highways, it is essential that the machine operate in such a manner as to eliminate only these bumps, ruts and the like and so that the tools employed do not and cannot gouge into the surface covering to make depressions in the highway and 35 so that the cutting tools, graders or the like employed may be accurately set to correspond with the crown of the road or highway which it is desired to surface.

40 It is therefore an object of this invention to provide a machine for surfacing or grading highways for eliminating ruts, bumps and the like, which machine is adjustable to an extremely fine point of precision so as to 45 enable the cutting tools carried by the machine to be adjusted to the exact crown of the road and so that the tools will be positively held at the adjustment provided in order that the same will act uniformly to surface or 50 grade the road without danger of the tools cutting into the surface to remove large portions of the surface highway and which machine carries a plurality of tools adjustable in such a manner so as to enable the truing of

the surface without danger of the tools operating to break the bond between the surface covering of the road and the base. 55

Another object of this invention is to provide a machine of such a character that the same may be employed for removing the surface covering of asphalt or the like from the base, such as concrete, when it is desired to resurface the road due to imperfect application of the surface covering or due to wear on the surface covering which has made it advisable to remove the surface covering and replace the same. 60

Other objects and advantages of this invention will be apparent from the following detailed description of a preferred embodiment thereof as illustrated in the accompanying drawings, in which drawings: 70

Figure 1 is a top plan view of a road working machine embodying this invention.

Figure 2 is a side elevation thereof.

Figure 3 is a rear end elevation thereof.

Figure 4 is a sectional end elevation taken substantially on the line 4—4 of Figure 1, illustrating the manner of mounting the scraper so as to permit accurate adjustment of the cutting surface thereof. 80

Figure 5 is a sectional side elevation taken substantially on the line 5—5 of Figure 4.

Figure 6 is a sectional end elevation taken substantially on the line 6—6 of Figure 1. 85

Figure 7 is a sectional side elevation taken substantially on the line 7—7 of Figure 1.

Figure 8 is a fragmental top plan view on an enlarged scale illustrating the manner of mounting and assembling the individual scarifying bars and illustrating the control and support bar as broken away. 90

Figure 9 is a perspective view of scarifying gripping members embodying this invention. 95

In the preferred embodiment of this invention shown in the drawings A illustrates the main frame of the machine, in which frame a scraper unit B, a scarifying unit C and a pair of disc cutting units D are mounted, the frame A being supported at or near its respective ends by roller units E and F, respectively. A draft connection 1 is provided at the forward end of the frame for connecting the same with a tractor or other suitable source of draft power. 100

The frame A is composed of spaced longitudinally extending channel irons 2 which extend throughout the length of the machine 105

and provide the main frame members for the vehicle. Secured to the lower transverse extensions 3 of the said channel irons 2 by any suitable manner, such as bolts, rivets or the like, are running shoes 4, which running shoes 4 are provided for sliding over the raised surfaces of the road or the like when the frame is adjusted in position so that on encountering irregularities in the road, 10 the shoes 4 engage the road, thus providing a sled which prevents the lowering of the working tools into the road surface when any particular wheel or roller of the units E or F encounters a considerable depression in 15 the road surface. The channel irons 2 are held in spaced relation by means of the transverse frame members 5, 6, 7, 8 and 9 and are spaced throughout the length or extension of the said channel irons 2. The transverse 20 frame member 6 provides a platform and is of sufficient width to permit the standing thereon of an individual to permit regulation during the travel of said machine of the rear frame unit F as will hereinafter be described. The frame members 7 and 8 are secured to a tool box 11 and are of U-shape so as to permit the upper surface of the tool box 11 to provide a suitable platform upon which an individual or individuals may 25 stand for manipulation and regulation of the units C and D, respectively. The transverse frame member 9 provides merely a brace at the rear end of the frame A.

The scarifying unit C comprises a heavy 30 steel block 12 which may be cut out as illustrated at 13 so as to regulate the weight thereof. Plates 14 are secured to the upper and lower ends of the block 12. The upper and lower plates 14 are provided with a series of recesses 15 at their opposite edges which extend over and beyond the edge faces of the block 12. The recesses 15 in the upper and lower plates 14 on one side of the block 15 are formed in vertical alignment and are spaced equally throughout the length of the plates 14. The recesses 15 formed on the opposite edges of the upper and lower plates 14 are formed in staggered relation to the recesses formed on the opposite side and are 40 also in vertical alignment so as to support bar scarifying members 16 in staggered relation on opposite sides of the block 12.

The bar scarifiers 16 are preferably of the following construction:

45 Each bar 16 comprises a shank 16^a which is approximately square in cross-section and fits within the vertically aligned recesses 15 formed in the upper and lower plates 14. At the lower end of the shank 16^a, the scarifying members are bent to an angle of about 45° from the vertical and are flattened out to provide chisel edges 16^b.

50 Means are provided for adjustably mounting the scarifying members 16 and for rigidly maintaining the same in the adjusted posi-

tion. These means comprise locking bars 17 which are secured in position by means of bolts 18 which pass through the block 12 and between the spaces provided between the spaced recesses 15 of the plates 14, the heads 19 of the bolts being countersunk in the face of the block 12. In this manner the bolts 18 are staggered throughout the length of the block 12 and the alternate bolts 18 are countersunk in the opposite faces of the block 12 70 so as not to interfere with the positioning of the scarifying members 16. The chisel edges 16^b of the scarifying members 16 are all adjusted to a uniform position or level and are then locked in the adjusted position. In order to accomplish this adjustment, a board is placed in a level position on the ground or elsewhere and the scarifying members 16 placed within their respective recesses 15 75 and rested upon the surface of the board. The gripping members 20 are then inserted behind the bars 17 in engagement with the shanks 16^a of the scarifying members 16. The gripping members have teeth 21 formed on their inner surface so as to bite into the surface of the shank 16^a to prevent the dislodgment of the scarifying members 16 from the adjusted position. The gripping members 20 are composed of a bar of steel or like material tapered through their length and provided on one face with gripping teeth 21 and on the opposite face with a projection 22 which provides a stop and is engaged against the upper edge 23 of the bar 17 to prevent their dropping out when the locking bars 17 80 are released to adjust the said gripping members. The gripping members 20 are driven into position from their under edges when the scarifier members 16 have been adjusted and their taper prevents their vertical displacement.

The provision of the gripping members 20 is an important part of my invention in that it provides a gripping means which prevents the moving of the scarifying members 16 or the chisel edges 16^b thereof from the adjusted position and insures that the scarifying unit C will present a uniform cutting edge throughout its length which will evenly and uniformly cut or scarify the surface of the road to the required depth and that when any particular scarifying members 16 encounters a rock or other projection on the surface of the road that the same will cut off this projection and will not be forced from the adjusted position, thereby assuring me of an even cut or grading of the surface of the road or highway and likewise insuring me that one scarifying member 16 will not be at a level below the others to form a ridge or groove in the surface of the road or highway. In securing the scarifying members 16 in position, the same are first placed in their respective recesses 15 and the gripping members 20 are positioned in place. The bolts are 85 90 95 100 105 110 115 120 125 130

then tightened until a firm grip is had between the gripping members 20 and the shank 16^a of the scarifying members 16. The lower bolts 18 in the lower end of the block 12 are then tightened to prevent vibration of the scarifying members 16 at their lower ends. The gripping members are then driven up with a sledge or the like from the under end against their taper so that the same scarifier members are wedged in position.

The block 12 is at its respective ends provided with bores 23^a to which screws 24 project. Recesses 25 are provided approximately intermediate the bores 23 in the blocks 12 and threaded blocks 26 are inserted within and maintained in these recesses 25. The screws 24 are screw-threaded through the blocks 26 and are journaled on end-thrust bearings 27 mounted upon transversely extending U-shaped frame members 28. Collars 29 are rigidly secured to the screws 24, being provided to prevent relative longitudinal movement of the screws 24 through the frame members 28. The frame members 28 are twisted at right angles at 30 and extend downward and are rigidly secured to the channel irons 2 of the frame A by means of bolts 31. Brace members 32 are provided which are rigidly secured to the downward extension of the frame members 28 at 33 and to the channel irons 2 of the frame A. Hand wheels 34 are provided for adjusting the height or position of the chisel points 16^b relative to the surface to be scarified.

In order to prevent endwise displacement of the block 12 relative to the frame A, guide members 35 and 36 are provided at the front and rear, respectively, of the block 12 on each side of the frame A and engage the sides of the block 12 so as to guide the same vertically during the adjustment thereof. The block members 35 and 36 are preferably cast in such a form as to provide upper and lower strain positions 37 and 38. The strain position 37 of each of the members 35 and 36 being so as to absorb a greater strain than the sections 38, the strain position 37 of each of the guide members 35 and 36 being positions so as to compensate for the position of the strain imparted to the scarifying members 16. That is, the position 37 of the guide member 35 is at the upper end of the block 12 while the position 37 of the guide member 36 is at the lower end of the block 12. By this process, the torsional strain imparted to the guide members 35 and 36 is adequately compensated for.

In order to permit adjustment of the opposite ends of the block 12 to different levels so as to accurately align the chisel edges 16^b with the crown of the road on which the same is being employed, the block 12 is of a less length than the distance between the channel irons 2 of the frame A. This permits a different regulation of the screws 24 by the

wheels 34 permitting the block 12 to be inclined so as to compensate for the crown or incline of the surface of the road or highway. The units D are disc carrying units which are similar to the scarifying units C except that the same carry discs 42 on which shafts 39 are journaled in bearings mounted in the U-shaped frame members 40 which is similar to the U-shaped frame member 41 which supports the rollers of the units E and the manner of adjustment to correspond with the crown or incline of the road is exactly similar to that of the units E and F and will be described with the description of the units E and F. The units D are employed principally when it is desired to remove the surface of the roadway from the base thereof and are for the purpose of breaking up the surface after and before the same is removed from the base by breaking the bond of the base from the surface. The forward unit D is employed for producing longitudinally extending openings in the surface of the road which is then loosened from the base by the scarifying unit C and the loosened surface is then pulverized by the rear unit D and the remaining traces of the surface are scraped from the base by the unit B. The provision of the two units D enables me to very efficiently and completely remove the surface from the base of a road or highway when it is desired to re-surface the same with asphalt or the like.

The units D may also be employed when it is desired to make a heavy cut in the surface of the roadway without removing the surface. This is done by adjusting the same so that only a slight cut is made in the surface which is then loosened by the scarifying unit C, the second unit D acting to pulverize the portion of the surface removed by the unit C and the unit B acting to scrape the surface to a level or smooth condition, removing the material that has been cut and pulverized by the units C and D.

The unit B or the scraping unit, is preferably of the following construction and comprises a blade 43 which is mounted between the channel irons 2 and is provided with a scraping edge 44.

The blade 43 is secured to a plate 45 by means of bolts 46 spaced throughout its length. Bores 47 are formed in the block 45 at spaced points. Threaded blocks 48 are mounted in recesses 49 formed in the block 45 and screws 50 passing to the bores 47 are screw-threaded through the blocks 48 for raising or lowering the scraper blade 43. The screws 50 at their upper ends pass through a transversely extending and angled bar 51 and are maintained against vertical movement through the bar 51 by means of collars 52 and end-thrust bearings 53. The screws at their upper ends are provided with wheels 54 for rotating the screws 50 to adjust the height and position of the scraper blade 43.

Thrust guide-bars 55 and 56, similar to the thrust guide-bars 35 and 36, are provided for guiding the scraper blade 43 during its vertical movement. The scraper blade assembly, like the scarifier assembly, being of slightly less width than the distance between the eye-beams 2 so as to permit of angular adjustment of the scraper blade to correspond to the crown and incline of the surface of the road-way or highway upon which the machine is being operated. Braces 57 are provided for bracing the transverse bar 51 which is secured to the upper portion of the channel irons 2.

The rear roller unit E is preferably of the following construction:

The shaft 58 is fixed at its ends in a U-shaped frame 41 and is secured at or near the center by means of a supplementary U-shaped bracket 60 to the frame 41 as illustrated in Figure 3. Guide-bars 61 are secured to the channel-irons 2 in the opposite sides of the U-shaped frame member 41 to prevent longitudinal movement of the U-shaped frame 41 and so as to guide the U-shaped frame during vertical adjustment. Broad-faced rollers 62 are journaled on the shaft 58 near the respective channel irons 2 and provide, in addition to means for supporting the machine, crushing rollers which crush and reduce to a fine state of subdivision the portions of the material scraped from the surface of the highway.

In order to permit and obtain a vertical adjustment of the rollers 62 so as to regulate the position of the channel irons 2 in respect to the surface of the road or highway and so as to incline the frame of the machine so that the same will correspond to the crown or incline of the road surface, I provide the following preferred means which comprise spaced screws 63, which are screw-threaded into blocks 64. The blocks 64 are secured by means of bolts 65 to the U-shaped frame 41 and the screws 63 extend through bores formed in the upper section of the U-shaped frame 41. A U-shaped adjusting means supporting frame 65^a is secured to the spaced guide-bars 61 at its upper end as illustrated at 66. The screw 63 is provided with collars 67 and end-thrust bearings 68 which prevent vertical movement of the screws 63 relative to the frame 65. Hand-adjusted wheels 69 are provided for actuating the screws 63 to raise or lower the wheels 62. As in the case of the units B and C, the U-shaped frame 41 is of less width than the distance between the channel irons 2 so as to permit either of the screws 63 to be adjusted so as to incline the shaft 58 to correspond with the incline or crown of the roadway over which the machine is being operated.

In order to prevent the material, such as asphalt, which is scraped from the highway or road from adhering to the broad-faced roller 62, I provide a tank 70 which is mount-

ed upon the frame 65^a, and which tank 70 is connected through conduits 71 to drip nozzles 72 which extend over the surface of the rollers 62 so that the water from the tank 70 drips upon the surface of the roller 62 to maintain the same wet or moist so as to prevent adhesion of the asphalt to the surface of said rollers. Each of the conduits 71 is provided with a valve 73 for regulation of the flow of water or other liquid.

The forward roller unit F is similar to the rear unit E except that the rollers 62 of the gear unit E are replaced in the forward unit by means of caster rollers 74 which are supported in caster-forks 75 which are secured at pins 76 to the U-shaped frame member corresponding to the U-shaped frame member 41 of the unit E but not illustrated. The matter of adjustment of the height and position of the caster 74 relative to the surface of the roadway is entirely similar to that provided for the rear roller unit E.

Having fully described a preferred embodiment of this invention, it is to be understood that I do not wish to be limited to the exact details of construction herein set forth, which may obviously be varied without departing from the spirit of my invention as set forth in the appended claims.

I claim:

1. The combination with a road working tool of a scarifying unit comprising a rectangular block, top and bottom plates being secured to and projecting at their sides over the side of the said block and having recesses formed therein, the recesses of the lower plate being vertically aligned with the recesses in the upper plate, bar scarifier members mounted in the said recesses, and means for holding the bar scarifier members within the said recesses.

2. The combination with a road working tool of a scarifier unit comprising a rectangular block, top and bottom plates secured to and projecting at their sides over the sides of the block, each of said plates having a plurality of recesses formed therein, the recesses of the upper and lower plates on the same side of the block being vertically aligned and the recesses in the said plates on the opposite side of the said block being formed in staggered relation, bar scarifier members mounted in the said recesses, means for holding the bar scarifier members within the said recesses, and gripping means for holding the bar scarifier members from vertical displacement.

3. The combination with a road working machine of a scarifying unit comprising a block formed of heavy steel and having upper and lower plates secured into and extending over the sides thereof, vertically aligned recesses formed in the overlapping edges of the said plates, scarifier bars mounted in the said recesses, locking bars secured in posi-

tion relative to the said block by means of bolts extending through the said blocks, and gripping members mounted between the said locking bars and the said scarifier members.

5. 4. The combination with a road working machine of a scarifier unit comprising a block having upper and lower plates secured thereto, the said plates having sides which extend beyond the sides of the said block, 10 the extending sides having vertically aligned slots into which bar scarifier members are adapted to be positioned and held.

5. The combination with a road working tool of a scarifying unit comprising a block 15 having upper and lower plates secured thereto, which plates have sides which extend beyond the sides of the said block and which extending sides have vertically aligned slots therein formed to a depth in vertical alignment with the sides of the said block, scarifier members positioned within the said recesses and engaging the side face of the said block, and means for maintaining the said scarifier members in position within the slots 20 and against the side faces of the said block.

6. The combination with a road working tool of a block, upper and lower plates secured to the said block, the said plates having

sides which extend beyond the said block 30 on both sides thereof, vertically aligned slots formed in the said plates on the opposite sides thereof in staggered relation, bar scarifier members mounted in the said vertically extending slots in staggered relation, locking bars, and means extending through the said block in staggered relation for maintaining the said locking bars in position in engagement with the bar scarifier members to maintain the same within the said recesses.

7. The combination with a road working 40 machine of a scarifying unit comprising a block, a plurality of bar scarifier members, a plurality of tapered gripping members, a locking bar extending across the said block and adjustably secured to the said block, the 45 said gripping members being interposed between the locking bar and the scarifier member and being driven into position with their smaller ends ahead, and means for holding the said gripping members from dropping 50 from position when the said locking bar is released.

Signed at Los Angeles, California, this 4 day of December 1925.

EARL A. WHEELER.
